OF MUNICH, GERMANY

CAR COUPLING

Application filed October 18, 1928, Serial No. 313,235, and in Germany November 7, 1927.

The present invention refers to a coupling for cars, especially railway cars, and comprises a tug-iron or hook, a tong-like gripper and a linked connection between the tug-iron and gripper, adapted to keep the gripper closed by the weight of the hook.

The accompanying drawings show one form of the coupling according to the present invention.

10 Fig. 1 being a side-view with horizontal tug-iron,

Fig. 2 a plan-view of Fig. 1, and

Fig. 3 a side-view with the gripper closed.

The tug-iron 3 is mounted on and can turn about a horizontal axle 2, connected to the underframe 1 of the car. A link bar 5 is hinged at point 4 to the tug-iron 3; the free end of link bar 5 is connected by joint to a lever 7 fixed on an axle 6. Swinging levers 8 are rigidly connected to both ends of the axle 6, said levers being connected together by a rod 9. To each lever 8 is connected a bar 10, each bar 10 being pivoted to a gripper shank 12 swinging about the axles 11.

To the lever 7 rails 14 are connected by bearing pieces 13, on which rails a weight 16 carried by a roller 15 can glide to and fro.

30 The axles 11 of the gripper shanks 12 are adjustable in bore holes 17 and the pivots of the bars 10 in bore holes 18, so that the length of the gripper can be altered according to the length of the buffers. Also, the pivot of the joint 4 of the link bar 5 is carried in a slot 19 of the tug-iron. This makes it possible to swing the tug-iron upwards without influencing the gripper. The head 20 of the tug-iron 3 can swing about an axle

40 21, so that the tug-iron has a certain amount of play with reference to the gripper when passing through curves and the like. The two lateral shanks of the tug-iron 3 carry rollers 22, which facilitate the engagement and disengagement of said tug-iron with the gripper of the next car.

The coupling is operated by means of the lever 8, by either exerting a pull on the connecting rod 9 or a pressure on the extensions 8' of the levers 8.

When uncoupled (Fig. 3) the tug-iron 3 occupies a downwardly slanting position, pressing through its own weight and by means of the bar 5 on the lever 7, so that the lever 8, which is connected to lever 7 by the 55 axle 6, presses the connecting rods 10 forwards in the direction of the arrow 23, thereby keeping the gripper shanks 12 closed (Fig. 2 in dotted lines). The weight 16 is now at the right end of the rail 14, near 60 to the tug-iron 3, so that almost the whole weight presses upon the tug-iron 3.

To open the gripper 12, lever 8 is swung into the position shown in Fig. 1, raising the tug-iron to a horizontal position and 65 opening the gripper shanks 12 by means of the bars 10 (Figs. 1 and 2). The rail 14 is hereby inclined downwards from right to left, so that the weight 16 glides as far as possible to the left, in which position it 70 maintains the tug-iron in the horizontal position.

The new coupling has the advantage that the engagement is automatic when two cars are pushed together. At the same time, the 75 coupling is of very simple construction and very reliable in action. Gripper and tug-iron can, when coupled, follow the movement of the buffers, that is to say, move sideways with reference to each other, without endangering the reliability of the engagement.

80 What I claim is:

In a car coupling a tug-iron, a gripper, a linked connection between them, a guide rail and a running weight on the same, adapted 85 to press only slightly on the tug-iron when engaged, but heavily when disengaged.

In testimony whereof I hereunto affix my signature.

ADAM AMRHEIN. 90
